UNITED STATES PATENT OFFICE

2,660,326

TAIL GATE LOADER AND PACKER

John P. Calamore, Flushing, N. Y., assignor to
 City Tank Corporation, Corona, N. Y., a corporation of New York

Application November 10, 1949, Serial No. 126,496

6 Claims. (Cl. 214—519)

1

This invention relates to a tailgate loader and more particularly to a tailgate loader and auxiliary packer for refuse trucks.

It is an object of this invention to provide a tailgate loader and specifically a tailgate loader for a refuse truck in which a prime mover operates a packer plate in a hopper to permit of the maximum filling capacity of the hopper and which efficiently translates rotary movement of a drive shaft into a compacting motion whereby high "pay loads" may be filled into refuse trucks economically.

It is contemplated by my invention to provide a refuse truck with a tailgate loader and packer including, in combination with a primary hopper and a feed therefrom comprising continuous flights, of a packer plate operating in a secondary hopper characterized by driving the packer from a countershaft transmitting movement to the plate with high efficiency, and guiding the plate during shifting of the load from the secondary hopper to give to the packer plate a combination downward, forward and upward movement, cyclically repeated, whereby refuse trucks may be quickly and efficiently charged and loaded.

Still more particularly it is an object of my invention to provide for combination with a refuse truck of a tailgate construction, a loader and packer including a primary hopper which may be located at a low level, a discharging lift comprising flights for removing the refuse from the primary hopper and directing it to a higher level position and discharging the same into a secondary hopper from which a cyclically operating packer plate serves to scrape clear the secondary hopper, while removing the charge therefrom by a combination downward, forward and upward pushing motion, further characterized by the operation of the packer plate by an eccentric having its power take-off by a countershaft operating the lifts for the primary feed.

Still more particularly it is an object of my invention to provide a load packer for refuse trucks comprising a primary hopper within which a packer plate is driven by a countershaft, and to transmit to the packer plate a movement to provide maximum filling capacity of the hopper and efficient scraping and packing action from said hopper into the refuse truck body.

To attain these objects and such further objects as may appear herein, or be hereinafter pointed out, I make reference to the accompanying drawing forming a part hereof, in which—

Figure 1 is a fragmentary side elevation, partly in section, of a tailgate embodying my invention;

2

Figure 2 is a magnified section taken on the line 2—2 of Figure 1;

Figure 3 is a section taken on the line 3—3 of Figure 2;

Figure 4 is an elevational view taken along the line 4—4 of Figure 3;

Figure 5 is a section taken along the line 5—5 of Figure 4.

The device of my invention may be summarized as providing a packer and combination tailgate loader particularly suitable for loading refuse into trucks and comprising a tailgate having a primary hopper located at a low level, with a feed by continuous flights which takes the load from the hopper and raises it into the truck body, depositing it into a secondary hopper in which there operates a packer driven in a manner to permit maximum filling capacity of the secondary hopper, with a scrapping action which gives the load a combination downward, forward and upward pushing action, cyclically repeated to shift the load into the interior of the truck body. The auxiliary packer may have utility by itself at any point along the height of the tailgate, whether used with or without a continuous flight loader. In the combination, the features of the invention involve the use of a single power driven shaft for operating the lifts, with simple countershafts for operating the packer, to provide the combination downward entrapping movement, for engaging the charge in the hopper with rearward compacting motion and upward pushing and return clearing motion, cyclically performed.

Making reference to the drawings, I illustrate my invention in a refuse truck 10 having a tailgate 11 hinged adjacent the top of the truck by a hinge 12. The tailgate includes a casing 13 leading downwardly to a hopper 14, having a filling trough 15 or hopper located at a low level of the truck. The casing side plates 16 and 17 support a cross shaft 18 on which is mounted for rotation the sprocket wheels 19 and 20, over which are guided chains 21 and 22, having lifts or flights 23. The opposed end of the lifts are provided with shaft 24 having the spaced sprockets 25 and 26 guiding the chains 21 and 22, respectively. A sprocket 27 has a chain drive or belt 28 from the prime mover 29 in the form of an hydraulic motor housed within the casing 13.

The lifts or flights are guided along the rear wall 30 extended continuously with the bottom wall 31 of the hopper and upwardly to the throat 32 immediately above the breaking edge 33. The throat 32 leads to a secondary hopper 34 comprising the arcuate bottom wall 35 having a terminal edge 36 and side plates 37 and 38 constitut-

ing side flanges which are supported on counter-shafts 39 and 40 or crank arms each of which is supported in independent bearings on the plates 41 and 42. Each of the countershafts 39 and 40 has an independent sprocket 43 and 44, respectively. Sprockets 45 and 46 on the shaft 24 are connected to the sprockets 43 and 44 to transmit the rotative movement of the shaft 24 by chains 45a and 46a to the countershafts 39 and 40, and in turn rotate the side plates 37 and 38. The side plates 37 and 38 are relatively flush with the supporting plates 41 and 42, forming with the bottom wall 35 the secondary hopper previously described. The plates 37 and 38 support an eccentric shaft 47 transversely of the hopper 34 to be guided closely adjacent the arcuately formed bottom wall 35. A packer plate 48 is mounted on the cross shaft 47, to extend a scraper edge 49 in contact with the bottom wall 35 as it moves eccentrically about the countershafts 39 and 40.

The upper edge 50 of the packer plate is provided with a cross bearing 51 to receive the cross bar 52 which is extended into side arms 53 and 54, terminating into pivots 55 and 56, anchored in the bearings 57 and 58 supported adjacent the side plates 41 and 42 of the casing.

With the construction described, it will be observed that upon rotation of the shaft 24 in the direction of the arrow 59, the countershafts 39 and 40 will be driven by the sprockets 45 and 46 and the chains 45a and 46a connected therewith, to transmit to the side plates 37 and 38 a rotary movement. Crank arms on which side plates are mounted may be employed instead of the side plates. This rotation extends to the cross shaft 47 an eccentric movement, and in turn oscillates the packer plate 48 about the arms 53 and 54, pivoted respectively at 55 and 56, projecting the packer plate 48 to provide a downward movement of the rear face R as the edge 49 comes adjacent the break edge 33. Clockwise rotation when viewed as in Figure 3 of the plate 37 will project the face R adjacent the edge 36, with an upward and rearward motion toward the interior of the truck body. When the packer plate, by the cross shaft 47, is moved to the extreme inward position the throat 32 is open to the fullest extent, to permit of maximum filling capacity.

Where the packer plate is employed in combination with the continuous flights or lifts operated on the chain 21 and 22 from the primary hopper 15, the lifts 23 are provided in number found most advantageous with the capacity of the hopper 34. Synchronization is provided so that for every other blade of the lift there will be one revolution of the countershafts 39 and 40, with the further detail of timing of the lift to present a lift blade 23 adjacent the edge 33 when the cross shaft 47 is in a diametrically opposite position for one blade and in a pre-coincident position (as shown in Figure 3) as the second blade approaches the edge 23. Such timing has been found to provide efficient operation. The combined rotational and swinging action serves to secure highly efficient and forceful scraping as well as pushing action adjacent the bottom wall 35, to transmit a pushing force of high magnitude against the load charged into the secondary hopper where it finds greatest resistance, and against the resistance of the accumulated load within the truck body. The return upward tilting movement clearing the hopper bottom avoids and minimizes recycling or return of the debris back into the casing within which the lifts oper-

ate and this undesirable factor is minimized, if not entirely eliminated. The packer plate 48 is more or less self-cleaning during operation with a wide variety of debris or refuse which may be charged into the hopper 34.

It will be observed that by the installation provided, maximum force or torque is transmitted within the hopper 34 at the point where the maximum load is encountered.

The driving of the countershaft for the side plates 37 and 38 from a single power driven shaft 24 makes for a simple yet rugged construction, assuring continued use and long life.

It will be observed that while in the preferred form of packer construction I combine the same with the continuous flights or lifts, positioning the loading hopper for the flights at a low level and the auxiliary packer and loader adjacent the uppermost portion of the refuse truck, it will be understood that this is illustrative only and that one or more of such auxiliary packer plates may be positioned along the length of the tailgate, including direct loading employing the secondary hopper assembly at the lowest level, and as the sole means of loading and packing the refuse within the truck body, the rotary movement given to the scraping edge 49 minimizing return of any debris within the secondary hopper and its projection outwardly from the same.

The primary characteristic feature in the auxiliary hopper is to provide a scraping and pushing force along the surface or bottom wall of the hopper which minimizes recycling while avoiding obstruction between the side plates, and this action which is secured by the eccentric movement of the bottom edge while obtaining upward shifting of the top edge I refer to in the appended claims as a "bodily swinging support" for the packer plate R.

Having thus described my invention and illustrated its use, what I claim as new and desire to secure by Letters Patent, is:

1. In a refuse truck or the like, a tailgate, a loader and packer comprising a fill opening in the tailgate, a hopper, an arcuate bottom wall, side plates and a packer plate driven between said side plates by an eccentric adjacent one end of the packer plate, guiding the end along the wall and link support for the opposite end of the plate providing a swinging movement, said packer plate being cyclically driven to provide forward, upward pushing and return lifting clearing movement.

2. In a refuse truck or the like having a low level lift directed to a fill opening above the floor level, the combination having a loader and packer comprising a filling hopper, an arcuate bottom wall and side plates and a packer plate, a prime mover for said packer plate including a bodily swinging support whereby a downward, forward upward bodily pushing motion and return load clearing movement is cyclically transmitted to the packer plate during rotation of the prime mover.

3. In a refuse truck or the like having a low level lift directed to a fill opening above the floor level, the combination having a tailgate having an upper fill opening a hopper defined by an arcuate bottom wall and side plates, a packer plate guided adjacent the fill opening of said hopper and having an edge guided adjacent said wall, a prime mover for driving said packer plate and a bodily swinging support for said packer plate during movement by said prime mover.

4. In a refuse truck or the like, a loading hop-

per therefor having an arcuate bottom wall, side plates, means for rotating the side plates, an eccentric cross shaft supported across said side plates, a packer plate supported adjacent its lower edge on said cross shaft, and a swinging support for the upper edge of said packer plate.

5. In a refuse truck or the like, a loader and packer comprising, in combination, a primary hopper, a prime mover and chain operated lift within said hopper for lifting the load, an upper fill opening, a secondary hopper comprising an arcuate bottom wall adjacent the fill opening and side plates, a prime mover and drive from said prime mover to said lift, side plates for said secondary hopper to each side of said fill opening, each mounted on an independent countershaft driven from said primary shaft, a packer plate supported on a cross shaft eccentrically supported to revolve with said side plates and between the same, to guide the bottom edge 20 of said plate adjacent the bottom wall of said hopper, the upper edge of said packer plate being supported on arms swinging adjacent said side

plates, providing a bodily swinging support for the packer plate.

6. A refuse truck having a loader and packer with a fill opening in the truck tailgate above the floor of the truck body, wherein the packer is characterized by a plate which is swingingly supported adjacent the fill opening by an eccentric shaft at its lower end and by supporting links at its upper end between spaced side plates 10 to each side of said fill opening.
